CLAIM

The ornamental design for a metal trouser rack, as shown and described.

DESCRIPTION

FIG. 1 is a front, right and top perspective view of a metal trouser rack, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 2.

FIG. 11 is an enlarged view of detail 11 in FIG. 7.

FIG. 12 is another front, right and top perspective view of the metal trouser rack in a first usable state; and,

FIG. 13 is another front, right and top perspective view of the metal trouser rack in a second usable state.

The broken lines depict portions of the metal trouser rack that form no part of the claimed design.

The dot-dash broken lines in FIGS. 1, 2, 7, 9, 10 and 11 depict the boundaries of the enlargements that form no part of the claimed design.

1 Claim, 13 Drawing Sheets
